UNITED STATES PATENT OFFICE.

HERMAN E. BAUER, OF MARSHFIELD, WISCONSIN.

CUSHIONED HORSESHOE.

SPECIFICATION forming part of Letters Patent No. 620,878, dated March 14, 1899.

Application filed September 19, 1898. Serial No. 691,333. (No model.)

To all whom it may concern:

Be it known that I, HERMAN E. BAUER, a citizen of the United States, and a resident of Marshfield, in the county of Wood and State 5 of Wisconsin, have invented certain new and useful Improvements in Cushioned Horseshoes; and I do hereby declare that the following is a full, clear, and exact description thereof.

10 My invention has for its object to provide simple economical cushioned horseshoes that may be reset or calked. Therefore said invention consists in certain peculiarities of construction and combination of parts, hereinafter particularly set forth, with reference 15 to the accompanying drawings, and subsequently claimed.

Figure 1 of the drawings represents a plan view of one of my improved horseshoes having the cushion portion thereof half broken away; and Fig. 2, an elevation of the shoe, partly in section, the same being indicated by line 2 2 in the preceding figure.

Referring by letter to the drawings, A represents a malleable-metal horseshoe having the whole of its upper face on the same horizontal plane and provided with an upwardly-extending outer flange *b*, that is continuous from one heel end to the other of said shoe. 25 Supported on the flanged upper face of the shoe is a parallel cushion *B*, the material in this cushion being preferably a good grade of elastic rubber. There is no union of the shoe and cushion; but the nails employed to fasten 30 said shoe to a hoof of a horse pierce said cushion and hold it in place. The cushion is

simply a flat layer of rubber in the shape of the metal shoe, upon which it rests inside the upwardly-projecting flange.

The shoe herein shown is provided with a 40 toe-calk and heel-calks, although these calks may be omitted, as is sometimes the case.

The shoe being made of malleable metal, such as steel or wrought-iron, and not fast to the cushion, it may be reset or calked, or 45 both, at any time without detriment to said cushion, the latter being designed to outlast more than one shoe.

Having thus described my invention, what I claim as new, and desire to secure by Letters 50 Patent, is—

A malleable-metal horseshoe having the whole of its upper face on the same horizontal plane and provided with an upwardly-extending outer flange, together with a cushion 55 consisting of a flat layer of rubber conforming in shape to the shoe, this cushion being laid upon the correspondingly-flat upper face of the shoe out of union with the same within the confines of the flange thereof to have 60 contact with the hoof to which said shoe is applied, the latter and said cushion being held to said hoof by nailing.

In testimony that I claim the foregoing I have hereunto set my hand, at Marshfield, in 65 the county of Wood and State of Wisconsin, in the presence of two witnesses.

HERMAN E. BAUER.
